UNITED STATES PATENT OFFICE.

MORRIS P. HOLMES, OF CLAREMONT, NEW HAMPSHIRE, ASSIGNEE TO SULLIVAN MACHINERY COMPANY, A CORPORATION OF MASSACHUSETTS.

MINING MACHINE.

Application filed June 13, 1921. Serial No. 477,041.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

My invention relates to mining machines. It has for its object to provide an improved mining machine. A further object of my invention is to provide improved cutter chain and feed mechanism and improved controlling means therefor whereby the cutter chain speed may be kept normal in such a manner as to support the load on the feeding mechanism and thereby balance the feed. Further objects of my invention include the provision of an improved take-up mechanism and the provision of improved truck driving mechanism and improved controlling means therefor. These and other objects and advantages of my improved construction will, however, herein after more fully appear.

In the accompany drawings I have shown for purposes of illustration one embodiment which my invention may assume in practice.

In these drawings,—

Fig. 1 is a side elevation of my improved machine mounted in transport position upon a truck.

Fig. 2 is a side elevation on the opposite side of the machine when the latter is removed from the truck.

Fig. 3 is a plan view of the machine, the feeding and controlling mechanism being shown in section.

Fig. 4 is a detail sectional view on line 4-4 of Fig. 2.

Fig. 5 is a detail sectional view on line 5-5 of Fig. 2.

Fig. 6 is a vertical sectional view on line 6-6 of Figs. 2 and 3 showing the operative connections between the feeding and cutter driving mechanism, a part of the controlling mechanism being shown in elevation.

Fig. 7 is a rear end view partially broken away showing the take-up mechanism.

Fig. 8 is a sectional view on line 8-8 of Fig. 6.

Fig. 9 is a diagrammatic plan view showing the different positions of the machine during the cutting operations in a room or the like.

In this illustrative embodiment of my invention I have shown for purposes of illustration a machine of the general type described and claimed in my co-pending application Ser. No. 312,846, filed July 21, 1919, and comprising a mining machine of the room and pillar type including a frame or casing 1 provided with a bottom plate or shoe 2 adapted to support the machine and slideable upon the mine bottom or a transport truck 3. As shown, this frame is provided with a rigid forwardly projecting cutter bar 4, the latter carrying a cutter chain 5 equipped with the usual cutter bits 6 and rotatable around the bar by means of a cutter chain driving sprocket 7 beneath the rear end of the frame 1 and above the shoe 2. As illustrated the machine frame also carries at its front end a suitable motor, herein a longitudinally disposed horizontal electric motor, having an armature 8 and controlled by any suitable control mechanism 9 including a controller handle located at the rear of the machine. The armature is herein operatively connectable, through variable reaction mechanism of the type described in my above mentioned application, to the cutter chain driving sprocket 7, a feed operating member 10 herein in the form of a chain sprocket, and a truck driving member 11 herein also in the form of a sprocket. As shown a flexible feed member, herein for illustrative purposes shown in the form of the feed chain 12, is also operatively connected to the feed operating member and guided by cooperating guiding members herein in the form of idlers 13, 14, and 15 on the frame, in such a manner that, when the member 12 is suitably connected, the machine is adapted to be propelled by its own power relative to the member 12, the mine bottom, or the truck in a well known manner. Also through a chain connection 17 operatively connectable between the member 11 and the front truck wheels 18, the machine is adapted to propel its truck when mounted in transport position thereon.

It will be observed that the motor armature 8 is provided at its front end with a bevel pinion 19, herein meshing with a horizontally disposed lower bevel gear 20. This gear, as shown in Fig. 6, is in turn rotatably mounted in suitable bearings 21, herein of the roller type, concentric with the upper end of a vertical stud 22 having a threaded

lower end extending through adjustable bearings 23 and supported on the shoe 2. The upper end of this bevel gear 20 is also fixed, herein by a key 24, to a sleeve 25 coaxially disposed with and rotatable relative to the stud 22 and having a pinion 26 on a reduced portion of the sleeve. This pinion 26 in turn meshes with a plurality of slightly larger pinions 27, herein three, disposed 10 radially thereabout and rotatably mounted, as on removable bearing members 28 carried on a rotatable spider 29 which in turn has an upstanding rotatable sleeve 30 disposed coaxially with the stud 22 and between the 15 same and the pinion 26 and gear 20. As shown, roller bearings 31 are herein provided between the pinions 27 and the members 28 and both the bearings 31 and the members 28 are removably attached to the rotatable 20 spider 29 by screws 32. Herein, it will also be observed that the pinions 27 mesh with an internal gear 33, which is journaled on the lower end of the stud 22 and rigidly united, as by screws 34, with the cutter chain 25 driving sprocket 7, likewise journaled on said stud. The gear 33 is herein also provided with a depending portion 35 having a flange 36 at its periphery running close to the inner edge of a flange 37 formed on the 30 frame 1, the construction being such that thereby the entry of cuttings or the like into the gearing is effectually prevented at the same time that the gear and sprocket are made removable as a unit from the top of the 35 frame. Here, attention is also directed to the fact that the outer periphery 38 of the gear 33 is adapted to be engaged by controlling means, herein in the form of a band 40 brake 39, having one end operatively connected to the frame, as at 40, and its other end connected to a threaded controlling member 41, threaded in a nut 42, extending through a suitable aperture in the side of the frame and fixed, as by a suitable key 43 45 to a hand wheel 44 on the outside of the frame. As a result of this construction, it will be observed that the brake band must be applied to obtain any feed while the cutter chain is remaining idle. It will further be noted that the cutter chain driving sprocket 7 may be rotated or idle while the motor is running, the cutter chain driving sprocket being adapted to be driven at full speed when the member 29 is held stationary, and to have its speed varied as the member 29 is allowed to rotate faster or caused to rotate 50 more slowly.

Cooperating with the cutter chain driving mechanism is improved feeding mechanism. 60 As shown in Fig. 6 the sleeve 30 on the spider 29 carries on its upper end a small bevel pinion 45 which in turn constantly meshes with a bevel gear 46. This pinion is keyed as at 47 to a transverse horizontal driving shaft 48 (Fig. 3) which is in turn journaled

midway between its ends in a bearing 49 carried by a support 50 on the frame. As shown, this shaft 48 is also removable laterally through the side of the frame and has both of its ends extending through the sides 70 of the frame. Herein, ball bearings 51 are provided between the pinion 46 and the support 50 and the pinion 46 is also connected as by screws 52 to a rotatable clutch casing 53 herein carrying therein certain of the elements of a friction clutch 54 and cooperating with an inner member 55 carrying the other clutch elements. This inner member 55 is in turn suitably rotatably mounted on the shaft 48 as on a removable bearing 80 sleeve 56 and suitably connected as by a key 57 to a rotatable sleeve 58 on the feed operating member 10 which is herein shown as removably carried on the left-hand end of the shaft 48 and rotatably mounted in roller 85 bearings 59 in a fixed stepped member 60 closing an aperture 61 in the side of the frame and fixed to the latter. Herein this member 60 has an annular chamber or cylinder 62 formed therein receiving an annular friction controlling member or piston 63 adapted when fluid is suitably supplied to it, as hereinafter described, to compress or release the elements of the friction clutch at will and thereby cause the feed operating member 10 to be rotated with the shaft 48 when the friction is loaded or to enable the shaft to rotate independently of the member 10 when the friction is released.

Cooperating with the variable reaction cutter chain and feed mechanism and operatively connected to the friction 54 is an improved controlling or dragging friction. Constantly meshing with the bevel pinion 46 is a cooperating bevel pinion 64 freely 105 rotatable on a bearing sleeve 65 on the front end of a rearwardly located longitudinally extending horizontal stud 66 supported at its front end on the member 50 and at its rear end in a stepped member 67 fixed to the frame as by bolts 68. This bevel pinion 64 is also suitably connected as through screws 69 to a rotatable friction casing 70 carrying certain of the elements of a friction clutch 71, the other elements of which are carried by an inner member 72 carried on a sleeve 73 on the shaft and fixed to the fixed stepped member 67 as by a key 74. As in the case of the friction 54, it will also be noted that an annular piston member 75 is movable in an annular cylinder 76 in the member 67 and that movement of the piston 75 in its cylinder will accordingly operate to control the pressure exerted on the clutch members and the retarding effect of the clutch 71 on the shaft 48.

Cooperating with the friction mechanism described is an improved take-up and truck driving mechanism. The rotation of the shaft 48 is imparted through a key 77 to a 130

sleeve 78 which has a bearing 79 between it and the member 50 and is connected as by screws 80 to the rotatable casing 81 carrying one of the elements of a friction clutch 82, the other element of the clutch being carried by an inner member 83 which is in turn keyed as at 84 to a sleeve 85 on a take-up member 86 corresponding to and interchangeable with the member 10 and similarly journaled in bearings 87 in a stepped member 88 fixed to the frame. As shown, the connection of the two clutch elements is also controlled by an annular piston 89 movable in an annular cylinder 90 formed in the member 88, the mechanism corresponding to that heretofore described as controlling the clutches 54 and 71 and being also similarly controlled as hereinafter described. Attention is also directed to the fact that the truck driving member or sprocket 11 is carried on the end of the shaft 48 which extends beyond the take-up member 86, the same preferably being connected to the shaft as by a key 91 and a washer 92 held in place by a threaded member 93. As shown, the flange of a removable flanged bearing sleeve 94 for the take-up member also acts as a bearing for the sprocket 11.

Operatively associated with each of the three friction mechanisms described is a controlling mechanism of the type described in my above mentioned application but modified in certain respects to give an independent control of each friction. As shown in Fig. 5 each of these mechanisms includes a cylinder 95 operatively connected, by suitable passages 96 in the stepped members and piping 97 where necessary, to the annular cylinders in the stepped members. In each of these cylinders 95 is a piston 98 movable longitudinally thereof to expel a suitable liquid, as for instance oil, from the cylinder 95 when the handle 99 of the piston 98 is moved, suitable means such as a usual taper thread split bushing 100 being provided so that when the handle is turned, the piston will be held in any given position of adjustment. Thus, the frictions may be applied with great facility and in any desired sequence.

Operatively associated with the feed operating member 10 and the take-up member 86 is improved means for taking up the slack which the take-up member may at any time cause to be inserted in the flexible member 12. This means herein includes a pair of pivoted slack absorbing members having upstanding longitudinally swinging arms 101 on opposite sides of the frame at points in rear of the members 10 and 86. As shown these arms 101 are provided with arcuate upper ends 102 leading toward the members 10 and 86 and are formed on a hollow cylinder 103 forming a conduit for the flexible feed member 12 and extending

transversely through the frame at a point adjacent the rear thereof. As shown the arms 101 are herein normally held in their slack absorbing position by coiled springs 104 connected between the cylinder 103 and the frame.

In my improved construction the flexible feeding member 12, when the same is connected for cutting, as from right to left as shown, extends from the left hand rib, rearward from the lower sprocket 13, (Fig. 3) to the outer sprocket 14 (Fig. 2) up to the feed operating member 10, backward around the arcuate end 102 on the left hand slack absorbing member 101, around that arm 80 and down the latter to the axis of the slack absorbing member, through the hollow cylinder 103, up around and forward from the other arm 101 (Fig. 1 in dotted lines) to the take-up member 86 and from that member downward to the other member 14 on that side of the machine and then rearward to the idler 15 and the right hand rib. In sumping, i. e. during the starting cut, the left hand free end of the flexible feeding member 12 will be as usual connected at the face, as distinguished from the left hand rib, the connections on the machine being the same as above described in connection with transverse cutting. When the machine is mounted for transport, however, the flexible feed member will be thrown off of the take-up member 86 so that it will occupy the position shown in full lines in Fig. 1.

In the operation of my improved mechanism during sumping, the machine is fed into the coal under the control of the friction 54, the brake band being applied until the cutters engage the coal and the friction 71 being released as the feed picks up its load. When the machine is sumped in under the coal and connected for the transverse cut, it may be straightened in the cut preparatory to its transverse movement by applying the friction 82 to connect the take-up 86 and thereby 105 swing the machine. During the transverse cut, the machine will normally proceed under the control of the friction 54. If an obstruction is encountered during the transverse cut, however, angling of the bar is 110 readily obtained by applying the take-up friction 82 to swing the machine. During all of these feeding operations it will be noted that the effect obtained may be varied at any time by connecting or disconnecting the friction 71 in such a manner as to increase or decrease the drag of that friction, the latter friction acting to balance the cutter chain speed with the load on the feed friction 54 in such a manner that the same pull is exerted on the feed chain and on the dragging friction for the same load. It will also be noted that as distinguished from any previous case, the provision herein of the friction 71 enables a take-up to be 125 130

used, the friction 71 being necessary to control the take-up which is connected by friction 82. These and other uses and advantages of my improved construction will however be clearly apparent to those skilled in the art.

While I have in this application specifically described one embodiment which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:—

1. In a mining machine, feeding mechanism including a plurality of friction 20 clutches and a supplemental variably controllable dragging friction clutch operatively connected to one of the elements of said clutches and adapted on loading to retard the rotation of either of said clutches.

2. In a mining machine, feeding mechanism including a takeup and actuating means therefor including frictional controlling means, and a cooperating frictional controlling means adjustable at will and loadable 30 to retard frictionally the rotation of one of the elements of said frictional controlling means.

3. In a mining machine, feeding mechanism for feeding the same during cutting 35 transverse kerfs in opposite directions across a face including feed operating and takeup members rotatable on transverse axes, and a continuous flexible feeding member engaging both of the same simultaneously.

4. In a mining machine, feeding mechanism for feeding the same during cutting transverse kerfs in opposite directions across a face including frictionally controlled feed 40 operating and takeup members rotatable on transverse axes, and a continuous flexible feeding member engaging both of the same simultaneously.

5. In a mining machine, feeding mechanism including feed operating and takeup 50 members rotatable on coaxial transverse axes at different speeds, and a continuous flexible feeding member engaging both of the same and disposable in opposite directions from opposite ends of the machine frame during feeding in opposite directions across a face.

6. In a mining machine, feeding mechanism including flexible feeding means, a take-up operated thereby, and automatic 60 means for taking up the slack created by said take-up mechanism between the latter and said feeding mechanism as it is produced.

7. In a mining machine, feeding mechanism including flexible feeding means, take-up mechanism for inserting slack therein,

between said feeding mechanism and said take-up and means for automatically taking up the slack inserted in said flexible means as it is produced.

8. In a mining machine, feeding mechanism including a feed operating member a continuous flexible feeding member, and take-up mechanism for inserting slack there-in between said feed operating member and take-up, and means for automatically taking up the slack inserted in said feeding member as it is produced. 75

9. In a mining machine, feeding mechanism including a flexible feeding member, a take-up member engageable therewith and 80 rotatable on a transverse axis to create slack in said flexible member, and automatic means rotatable on a parallel axis for taking up the slack created.

10. In a mining machine, feeding mechanism including a flexible feeding member, a take-up operative to create slack therein, and automatic means operable in the same plane as said take-up member for absorbing the slack created. 85

11. In a mining machine, flexible feeding means, feeding mechanism including feed operating and take-up members cooperating therewith, and means moving in the plane of each of said last mentioned members automatically operative to absorb slack in said flexible means. 90

12. In a mining machine, a continuous flexible feeding member, feeding mechanism including feed operating and take-up members engageable therewith, and means movable in the plane of each of said last mentioned members for automatically absorbing slack in said flexible member. 100

13. In a mining machine, a continuous flexible feeding member, feeding mechanism including feed operating and take-up members engageable therewith, and a resiliently connected means movable in the plane of each of said last mentioned members for absorbing slack in said flexible member. 110

14. In combination, in a room and pillar mining machine, feeding means including winding members rotatable thereon on coaxial transverse axes and each alternatively operative as a feed operating or as a takeup member, and a continuous flexible feeding member engaging said members at points between its ends. 115

15. In combination, in a room and pillar mining machine, feeding means including winding members rotatable thereon on coaxial transverse axes and each alternatively operative as a feed operating or as a takeup member, a continuous flexible feeding member engaging said members at points between its ends, and means for varying the length of the portion thereof between said winding members. 120

16. A room and pillar mining machine 130

having feeding mechanism including feed operating and takeup members each directly drivable by power independently of the other, a continuous flexible feeding member 5 engaging said members, and means for supporting on said machine the portion of said flexible member extending between said members.

17. A room and pillar mining machine 10 having feeding mechanism thereon including feed operating and take-up members each directly drivable by power independently of the other, a continuous flexible feeding member engaging said members, and 15 means for supporting on said machine the portion of said flexible member extending between said members including a feed member guide on said machine.

18. A room and pillar mining machine 20 having feeding mechanism thereon including feed operating and take-up members on opposite sides thereof, a continuous flexible feeding member engaging said members, and means for supporting on said machine 25 the portion of said flexible member extending between said members including a transverse feed member passage on said machine.

19. A room and pillar mining machine 30 having feeding mechanism thereon including feed operating and take-up members, a continuous flexible feeding member engaging said members, and means for supporting the portion thereof between said members and on said machine including a passage 35 and guiding means between said passage and said members.

20. In a mining machine, a frame having 40 an aperture therethrough, feeding mechanism including feed operating and take-up members on said frame, and a flexible feeding member engaging said members and passing through said aperture.

21. In a mining machine, a frame having 45 an aperture therethrough, feeding mechanism including feed operating and take-up members on said frame, and a flexible feeding member engaging one of said members and passing through said aperture to the other thereof.

50 22. In a mining machine, a frame having an aperture therethrough, feeding mechanism including feed operating and take-up members on said frame, a flexible feeding member engaging one of said members and passing through said aperture to the other thereof, and means between said aperture and said first mentioned members for absorbing slack in said flexible member.

60 23. In a mining machine, a frame having an aperture therethrough, feeding mechanism including feed operating and take-up members on said frame, a flexible feeding member engaging one of said members and passing through said aperture to the other thereof, and resiliently connected means be-

tween said aperture and said first mentioned members for absorbing slack in said flexible member.

24. In a mining machine, a machine frame, feeding mechanism thereon includ- 70 ing a feed operating member and a take-up member, a continuous flexible feeding member cooperating with each of said members, and means for automatically absorbing slack in said flexible member created by said take- 75 up member.

25. In a mining machine, a machine frame, feeding mechanism thereon including a feed operating member and a take-up member, a continuous flexible feeding member, and 80 means carried on the side of said frame for automatically absorbing slack in said flexible member created by said take-up member.

26. In a mining machine, a machine frame, feeding mechanism thereon including a feed 85 operating member and a take-up member, a continuous flexible feeding member, and means carried on the side of said frame and movable in the plane of said take-up member for automatically absorbing slack in said 90 flexible member created by said take-up member.

27. In a mining machine, a machine frame, feeding mechanism thereon including a feed 95 operating member and a take-up member, a continuous flexible feeding member, and means carried on the side of said frame and movable in the plane of said feed operating member for automatically absorbing slack in said flexible member created by said take-up 100 member.

28. In a mining machine, feeding mechanism including a rotating shaft, feed operating and take-up members connectable thereto, and common frictional controlling means 105 loadable to positively retard rotation of either of said members.

29. In a mining machine, feeding mechanism including a rotating shaft, a feed operating member, a take-up member, means 110 for operatively connecting said members to said shaft, supplemental means controlling the rotation of either of said members when connected to said shaft, and a truck driving member carried by said shaft. 115

30. The combination with a room and pillar mining machine, of flexible feeding means thereon including feed operating and take-up members rotatable on co-axial trans- 120 verse axes bearing constantly the same relation to said machine frame and located on the opposite sides thereof, a continuous flexible feeding member, and means for operatively connecting the latter to said members to feed said machine laterally in either direction.

31. The combination with a room and pillar mining machine, of flexible feeding means thereon including feed operating and take-up members rotatable on co-axial trans- 125

8
verse axes and located on the opposite sides thereof, a continuous flexible feeding member operatively connected to said members, and means for actuating said members to feed said machine toward either end of said flexible member.

32. The combination with a room and pillar mining machine, of feeding mechanism thereon including feed operating and take-up members rotatable on co-axial transverse axes and located on the opposite sides thereof, a continuous flexible feeding element operatively connected to both of said members to feed said machine in either direction during a normal cutting operation, and means for rotating either member.

33. The combination with a room and pillar mining machine, of feeding mechanism thereon including independently controllable feed operating and take-up members rotatable on co-axial transverse axes and located on the opposite sides thereof, a continuous flexible feeding element operatively connected to both of said members, and means for rotating either member at different speeds.

34. The combination with a room and pillar mining machine, of feeding mechanism thereon including independently controllable feed operating and take-up members rotatable on co-axial transverse axes and located on the opposite sides thereof, a continuous flexible feeding element operatively connected to both of said members, and means for rotating said members simultaneously.

35. The combination with a room and pillar mining machine, of feeding mechanism thereon including feed operating and take-up members rotatable on co-axial transverse axes and located on the opposite sides thereof, a continuous flexible feeding element operatively connected to both of said members to feed said machine in either direction during a normal cutting operation, and means for rotating said members simultaneously or either of the same at will.

36. In a mining machine, a machine frame, feeding mechanism thereon including frictionally controlled feed operating and take-up members rotatable on transverse axes and located on the opposite sides of said frame, an idler located on a parallel axis adjacent each of said members, and a single continuous flexible feeding member engaging said members and said idlers.

37. In a mining machine, a machine frame, feeding mechanism thereon including feed operating and take-up members rotatable on transverse axes and located on the opposite sides of said frame, a continuous flexible feeding member engaging both of said members, guiding idlers therefor located on a parallel axis adjacent each of said members, and cooperating guiding means for directing

the opposite ends of said flexible member laterally from opposite ends of said frame.

38. In a mining machine, a machine frame, feeding mechanism thereon including feed operating and take-up members rotatable on transverse axes and located on the opposite sides of said frame, an idler located on a parallel axis adjacent each of said members, a flexible feeding member engaging said members and said idlers, and a slack absorbing member engaging said flexible member at a point between said feed operating and take-up members.

39. In a mining machine, a machine frame, feeding mechanism thereon including feed operating and take-up members rotatable on transverse axes and located on the opposite sides of said frame, an idler located on a parallel axis adjacent each of said members, a flexible feeding member engaging said members and said idlers, and slack absorbing members movable in the plane of said feed operating and take-up members and located on the opposite sides of the frame and respectively engaging said flexible feeding member as it passes off of said feed operating member and as it passes on to said take-up member.

40. A mining machine having a frame, feed operating and take up members thereon, a flexible feeding member associated therewith and comprising portions extending from said members and in opposite directions from opposite ends of said frame during cutting across a face and a portion intermediate said members, and means for guiding the last mentioned portion transversely of said machine and between the ends of said frame.

41. A mining machine having a frame, feed operating and take up members thereon, a flexible feeding member associated therewith and comprising portions extending from said members and in opposite directions from opposite ends of said frame during cutting across a face and a portion intermediate said members, and means for guiding the last mentioned portion transversely of said machine and between the ends and the upper and lower sides of said frame.

42. A mining machine having a frame, a flexible feed member associated therewith and comprising portions extending in opposite directions from opposite ends of said frame during cutting across a face and an intermediate portion, and a recess formed in said frame intermediate the ends thereof to guide said intermediate portion of the flexible member.

43. A mining machine having a frame, feed operating and take up members thereon, a flexible feeding member associated therewith and comprising portions extending from said members and in opposite di-

rections from opposite ends of said frame during cutting across a face and a portion intermediate said members, and means for guiding said last mentioned portion longitudinally and transversely of said machine frame and supporting it thereon.

44. In a mining machine, feeding mechanism including a plurality of clutches, and a supplemental clutch engagable to retard any of said clutches, said first mentioned clutches comprising driving elements and elements adapted to be connected with said driving elements to be driven thereby and said last mentioned clutch being engageable to effect retarding of said driving elements whether or not said other elements are connected for driving.

45. In a mining machine, feeding mechanism including a feed operating friction clutch and a takeup operating friction clutch, and a supplemental friction clutch loadable to retard either of said clutches.

46. In a mining machine, cutting mechanism, feeding mechanism mechanically con-

nected thereto and driven by the reaction thereof and including a plurality of friction clutches, and a supplemental friction clutch controlling either of said clutches.

47. In a mining machine, feeding mechanism including a plurality of frictional clutches, and a cooperating controlling frictional clutch connectable at will with one of the elements of either of said clutches.

48. In a mining machine, feeding mechanism including a plurality of frictional clutches, and a cooperating frictional clutch connectable at will to one of the rotating elements of one of said clutches and operative to retard the latter.

49. In a mining machine, feeding mechanism including a plurality of frictional clutches, and a cooperating frictional clutch connectable at will to one of the elements of said clutches and operative to retard said element.

In testimony whereof I affix my signature.

MORRIS P. HOLMES.
